UNITED STATES PATENT OFFICE.

JOHN KANE, OF PHILADELPHIA, PENNSYLVANIA.

FIRE-EXTINGUISHER.

SPECIFICATION forming part of Letters Patent No. 395,906, dated January 8, 1889.

Application filed October 9, 1888. Serial No. 287,701. (No model.)

To all whom it may concern:

Be it known that I, JOHN KANE, a citizen of the United States, and a resident of Philadelphia, Pennsylvania, have invented certain 5 Improvements in Fire-Extinguishers, of which the following is a specification.

My invention consists of an improvement in that class of fire-extinguishers known as "dry-pipe systems," in which the water or other extinguishing-fluid is normally prevented from entering the sprinkling-pipes of the system, the controlling-valve being kept in the closed position by devices under control of a piston or diaphragm acted on by a pressure of air in 10 the sprinkler-pipes or in a secondary system of pipes, likewise provided with plugs or valves retained in position by fusible solder, so that the lowering of pressure in the air-pipe, due to the escape of air therefrom on the 15 melting of one or more of the fusible retainers, will permit the release of the valve in the water-pipe and the flow of water into said pipe and through such of the sprinklers thereon as 20 may have been released by the heat.

25 The object of my invention is to provide simple and efficient means whereby the movement of the piston or diaphragm in the air system is caused to control the action of the valve in the water-pipe.

30 In the accompanying drawings, Figure 1 is a diagram showing sufficient of a dry-pipe-system fire-extinguisher to illustrate my invention. Fig. 2 is a similar view showing some of the parts in a different position, and 35 Fig. 3 is a detached perspective view of that part of the device to which my invention particularly relates.

A represents the water-pipe, which may have both a supply branch, A', from the street- 40 main and a supply branch, A², from an elevated tank. This pipe is provided with a number of sprinklers, a, of any desired character, kept closed by fusible retainers, a valve, b, being interposed in the pipe A between the 45 supply branch and the first sprinkler of the series, and this valve being normally closed, so as to prevent the passage of water beyond the same or its access to the system of sprinkler-pipes. The stem of the valve is connected to 50 a lever, B, one arm of which is provided with a weight, d, while the other arm is furnished with a bell-crank lever, D, forked at the ful-

crum, so as to present two short arms, which are notched at their upper ends for the reception of pins or trunnions f, projecting from 55 opposite sides of a weight, F, of such a character that the preponderance of weight is on that arm of the lever B carrying the lever D, so that the valve b is kept closed to its seat.

The upper or supporting ends of the short 60 arms of the lever D are, when the latter is in its normal position, as in Fig. 1, slightly inside of a vertical line passing through the fulcrum of the lever, so that the tendency of the weight F is to maintain the lever D in this 65 position. If, however, the inner end of the long arm of the lever D is lifted, so as to throw the upper ends of its short arms to the other or outer side of said vertical line, the tendency of the weight will be to continue the 70 movement until it is finally discharged from the short arms of the lever, and the valve-lever B is thereby relieved of the weight F, so that the weight d on the other arm of the lever acts to lift the valve b and permit the flow 75 of water into the pipe A and to the sprinklers. A dry-pipe system of this character is usually employed in connection with a supplementary air-pipe, G, which has distributed throughout its length valves s with fusible retainers, this 80 pipe communicating with any suitable pump or other air-forcing device, and having in the present instance a branch, h, upon which is mounted a casing, I, containing a flexible diaphragm, i, the stem of which is connected to 85 a lever, K, hung to a suitable bearing on the casing. A cylinder and piston may, as will be evident, be substituted for the casing and diaphragm, if desired.

One arm of the lever K is provided with a 90 weight, m, and its other arm is connected by means of a cord, chain, or other suitable device, n, to the long arm of the lever D, constituting the tilting weight-carrier of the valve B.

The normal pressure of air in the pipe G and within the casing I is sufficient to raise the diaphragm i therein, so as to lift the weighted arm of the lever K and relieve the chain n from tension; but upon the melting 100 of the fusible retainer on any one of the valves in the pipe G the air is permitted to escape from said pipe and from the casing I, and the pressure beneath the diaphragm i is thereby

that the weighted arm of the lever , thus pulling upon the long arm or D, tripping the same and dis-
lue weight F from the valve-lever, permit the valve to be opened by the
he weight d.

It is evident that with a device of this
sized pressure of water may be main-
tained only a slight pressure in the air-
m, i, can be employed, and the flexible
in the operation, due to the setting
ng of this diaphragm, is effectually
e.

use of the independent or supplement-
pipe, however, is not absolutely nec-
o the proper carrying out of my in-
. For instance, a pressure of air may
ly be maintained in the main or sprink-
le A, a connection for this purpose
represented by dotted lines in Fig. 1.
lve B, moreover, need not necessarily
lve in the water-pipe, as it might be
lve controlling the supply of steam to a
pump connected with the sprinkler sys-
ne valve being normally closed and only
d so as to put the pump in operation
there was such a reduction in press-
the air-pipe as to cause the operation
tilting weight-carrier on the lever-valve
the discharge of the weight therefrom.
her means may also be used for causing
diaphragm or piston to act on the tilting
ght-carrier, a cord and pulleys providing
rect connection between said carrier and
weighted stem of the diaphragm being
wn, for instance, by dotted lines in Fig. 1.
e use of the lever K is preferred, however,
it imparts a sudden jerk, which facilitates
ight-carrier and the dis-

trolling the flow of water into the same with
a valve-lever, a tilting weight-carrier hung
thereto and having a weight loosely mounted
upon it, whereby the valve is kept closed, an
air-pipe having discharge-valves with fusible
retainers, a casing communicating with said
air-pipe and having a yielding diaphragm or
its equivalent, and means whereby the move-
ment of said diaphragm is transmitted to the
tilting weight-carrier of the valve-lever, and
thus causing the discharge of the weight
therefrom and permitting the opening of the
valve, all substantially as specified.

2. The combination of the sprinkler-pipe,
its valve-lever, a tilting weight-carrier pivoted
to the latter and having a weight loosely
mounted upon it, whereby the valve is held
closed, the air-pipe with its casing and dia-
phragm, and a weighted lever acted on by the
stem of the diaphragm and connected to the
tilting weight-carrier of the valve-lever, all
substantially as specified.

3. The combination of the sprinkler-pipe,
its valve and valve-lever, the air-pipe having
discharge-valves with fusible retainers, a cas-
ing communicating with said air-pipe and
having a yielding diaphragm or its equiva-
lent, a lever fulcrumed on the valve-lever and
having a forked short arm, a weight having
trunnions mounted upon said forked arm, 75
and serving when in position thereon to de-
press the valve - lever and keep the valve
closed, and means whereby the movement of
the diaphragm is transmitted to the weight-
carrying lever to effect the lifting of the same
and the discharge of the weight therefrom, all
substantially as specified.

In testimony whereof I have signed my name
to this specification in the presence of two sub-
scribing witnesses.

JOHN KANE.
